UNITED STATES PATENT OFFICE.

JOSEPH N. BROWN, OF DODGEVILLE, WISCONSIN.

ARTIFICIAL SNAKE, &c.

No. 857,593.

Specification of Letters Patent.

Patented June 26, 1907.

Application filed April 4, 1906. Serial No. 309,819.

To all whom it may concern:

Be it known that I, JOSEPH N. BROWN, a citizen of the United States, residing at Dodgeville, county of Iowa, and State of Wisconsin, have invented new and useful Improvements in Artificial Snakes, &c., of which the following is a specification.

My invention relates to improvements in artificial snakes and other animals, or parts of animals having numerous articulated joints.

The object of my invention is to provide a device which may be used as a toy or as a confection, and which will represent a snake or other reptile, or an articulated neck or tail of some animal, the device being especially designed for use in the preparation of confections, in that it provides means for connecting a series of separable parts in a manner to attract attention and secure a ready sale.

In the following description reference is had to the accompanying drawings, in which,—

25 Figure 1 is a top view of my invention. Fig. 2 is a detail side view with one of the members removed to show the connecting web. Fig. 3 is a cross sectional view drawn between two of the members and showing the connecting web. Figs. 4 and 5 are views similar to Figs. 2 and 3 showing modified means for connecting the several members.

Like parts are identified by the same reference characters throughout the several views.

35 The device is formed of a series of members, each composed of two semi-cylindrical sections A and B, separated from each other in whole or in part by a flexible connecting band C, which serves to unite the various members in a lineal series. At one end the sections A and B are tapered inwardly toward the connecting band as indicated at a and b. The several sections are preferably cut off square at their rear ends, presenting a surface extending substantially at right angles to the connecting band, so that the tapered or beveled surfaces a and b of each succeeding member diverge outwardly from the connecting band and from the rear end wall of the preceding member, thus allowing the members to swing relatively without cramping or binding against each other. In Fig. 1 a series of members are shown as they appear when arranged to represent a snake, an integral end member E being formed to represent the head of the snake, the same being

slotted at its rear end for the reception of the extremity of the connecting band. Another integral member F is formed to represent the tip of the tail, and the extremity of the connecting band extends into this member also, as clearly illustrated in Fig. 1. The intermediate portions formed in sections as above described, are arranged in a graduated series with the larger members in the central portion so that the series as a whole bears a resemblance to the contour of an ordinary snake. It will be observed that the end walls a and b of the respective sections and the rear walls of the preceding sections diverge from each other and from the connecting band in a vertical plane, thus permitting the sections to swing laterally, but not vertically.

If desired cords G may be substituted for the band C, and with this construction it will of course be understood that each member may be formed in sections or integrally as desired. Where my invention is embodied in a confection, the various sections A and B, as well as the end sections E and F, will of course, be formed of soluble material and constitute the confection proper, while the connecting member will be insoluble and will consist of paper, cloth or other fabric, which will permit the detachment of the several members by tearing across the band between the members.

Having thus described my invention what I claim as new and desire to secure by Letters Patent is,—

1. In a device of the described class, the combination with a series of members arranged lineally; and a flexible connection extending in a vertical plane centrally through the several members of the series; said members being provided with walls diverging in a vertical plane from each other and from said central connection.

2. In a device of the described class, the combination with a series of members arranged lineally; and a flexible connection extending in a vertical plane centrally through the several members of the series; said members being provided with walls diverging in a vertical plane from each other and from said central connection; together with end members of different character from the intermediate members and connected to the extremities of the flexible connection.

3. In a device of the described class, a confection comprising a series of soluble mem-

bers, each formed in sections; and an insoluble central and continuous band connecting the sections to each other and connecting the members in a lineal series; the contiguous walls of the members being arranged to diverge from the connecting band and from each other in a vertical plane; said band being formed of material which can be readily torn apart between the sections and of sufficient width in a vertical plane to support the

sections against relative vertical movements by permitting them to swing freely in a horizontal plane.

In testimony whereof I affix my signature in the presence of two witnesses.

JOSEPH N. BROWN.
